STOOL

James A. Campbell, Kewaunee, Wis., assignor of
one-half to Charles T. Campbell, Kewaunee,
Wis.

Application January 7, 1933, Serial No. 650,687

10 Claims. (Cl. 155—94)

The invention relates to improvements in supports for stools, chairs, tables and similar articles. More particularly the invention relates to improvements in supports for stools, chairs or the like wherein the length of the pedestal or seat supporting members are extensible within predetermined limits in combination with means for automatically locking such members against possibility of collapse under their weight or the 10 weight of an occupant thereof.

It is an object of the invention to provide an improved extensible support for stools, chairs or the like.

Another object of the invention is the provision of improved locking means for extensible supports of the kind described, said means being operable to prevent decreasing the length of the support under load and yielding under tension to permit further extension of the support between 20 predetermined limits.

A further object of the invention is the provision of improved fastening means for extensible supports of the kind described.

A still further object of the invention is the provision of improved means for locking extensible supports against collapse under compression exerted thereon and which will permit extensibility of the support under tensile force applied thereto when in normal vertical, inverted, or any intermediate position.

Many other objects and advantages of the construction herein shown and described will be obvious to those skilled in the art.

To this end my invention consists in the novel construction, arrangement and combination of parts herein shown and described, or uses mentioned.

In the drawings, wherein like reference characters indicate like or corresponding parts:

40 Fig. 1 is an elevational view of a stool embodying the principles of the invention;

Fig. 2 is a perspective view of another form of stool embodying the invention;

Fig. 3 is a longitudinal sectional view through the device shown in locking position;

Fig. 4 is a view similar to Fig. 3 with the locking portion in released position;

Fig. 5 is a sectional view along the line 5—5 of Fig. 3;

50 Fig. 6 is a sectional view along the line 6—6 of Fig. 3;

Fig. 7 is a perspective view of an element forming a portion of the locking device;

Fig. 8 is a view of a fragmentary portion of an alternative embodiment of the invention;

Fig. 9 is a fragmentary sectional view of another form of the invention;

Fig. 10 is a view along the line 10—10 of Fig. 9; and

Fig. 11 is a view along the line 11—11 of Fig. 9. 5

Referring now more particularly to the drawings, the numeral 10 designates a seat and the numerals 12 and 15 respectively designate the outer and inner telescoping members of an extensible support for the seat. The stool shown 10 in Fig. 1 is supported by a single extensible pedestal wherein the member 12 is preferably fastened to the floor by a base member 13 and bolts 14. The inner member comprises a locking rod 15 telescopically mounted in a locking box 16 or housing 21 surmounting the member 12. The member 12 is preferably cylindrical and the rod 15 extends substantially the full length thereof when the support is contracted to minimum height. The seat 10 is fixedly mounted on the 20 rod 15, the latter being provided for that purpose with a stem 16 on its upper end which projects through an opening in a member 17 forming the bottom of the seat. The end portion of the stem 16 is upset to form a riveted connection of 25 the stem with the member 17, such connection serving to fixedly fasten the seat to the rod 15.

The locking box or housing 21 has its lower end portion interiorly threaded for connection with an exteriorly threaded stem 22 projecting 30 from the member 12. The upper portion of the housing 21 has its inner periphery beveled as shown to provide a frusto-conical chamber 29. The upper end of the housing 21 is closed by a cap 24, preferably formed of sheet metal or the 35 like, and having its edge portion turned downwardly and inwardly to provide a converging flange fitting in a corresponding groove 25 on the outer periphery of the housing. The cap 24 is preferably split along a radial line (not shown) 40 to permit of its mounting upon the housing with its flanged edge taking the position shown in Figs. 3 and 4. The flanged edge of the cap 24 is sufficiently convergent to prevent its accidental removal from the housing but yields sufficiently 45 to permit removal by the application of force for that purpose. A pair of oppositely positioned grooves 18 extend the full length of the rod 15 for a purpose hereinafter more particularly described. The cap 24 is provided with inwardly 50 projecting key members 27 which close the slots for all extended and retracted positions of the rod 15, thereby preventing the possibility of articles dropping in or being inserted into the chamber 29 which might clog or otherwise interfere 55

with the proper operation of the locking or retaining mechanism located in the chamber.

The inner periphery of the housing 21 is shown as cylindrical adjacent to the beveled periphery 28 to provide a cylindrical surface 30 having a diameter somewhat greater than that of the rod 15 extending therethrough. The diameter of the inner periphery of the housing 21 is substantially reduced at the lower end of the surface 30, thereby providing a shoulder 31 and below the shoulder for a short distance, the housing has an inner periphery 32 of a still smaller diameter providing a close sliding fit for the rod 15. A lug 20 projects from the peripheral surface 32 into a groove 19 in the rod 15 and provides a key preventing rotation of the rod relative to the housing 21. The groove 19 is so positioned and of such a length as to permit the necessary telescoping movement of the rod 15 relative to the housing 21 and the member 12. The rod 15 has a diameter slightly smaller than that of the inner periphery of the member 12 and near its lower end is provided with an annular groove 46 in which an expansible spring band 41 is mounted. The frictional contact of the band 41 with the inner periphery of the member 12 is such as to require substantial force to move the rod 15 relative to the member 12 and thereby permits the stool to be lifted and carried by grasping the seat without movement of the rod in the member 12; the weight of the housing 21, member 12 and the supporting base 13 being insufficient to overcome the resistance due to the frictional contact of the band 41 with the inner surface of the member 12.

Means is located in the chamber 29 for retaining the rod 15 locked against downward movement in all extended positions up to the maximum and which permits extension of the support by movement of the rod 15 outwardly. The retaining means comprises a spring band or collar 33 located with its upper end in the chamber 29 and its lower end in sliding fit with the cylindrical surface 30 of the housing. The collar 33 is shown in perspective in Fig. 7 as comprising a cylinder cut along the longitudinal line 43. The collar 33 normally has a slightly larger diameter than that of the peripheral surface 30 and is slightly contracted when mounted therein. The tendency of the collar 33 to expand provides frictional contact with the surface 30 sufficient to require substantial force to move the band longitudinally of the housing.

A plurality of recesses 34 are provided in the upper end of the collar 33, each providing a seat for one of a plurality of ball bearings 36. The bottoms of the recesses 34 are inclined slightly downwardly and inwardly towards the rod 15 and the spacing of the collar 33 from the rod is such that gravity causes the balls to ride in the recesses in point contact with the rod. The lower end of the collar 33 has inwardly turned lugs or keys 35 extending into the oppositely positioned grooves in the rod 15. The balls are held in their position of contact with the rod 15 by a ring washer 37 resting against and held in position on the tops of the balls by a compressive spring 38. The compressive force exerted by the spring 38 is less than the resistance of the collar 33 to movement by reason of its frictional contact with the cylindrical peripheral surface 30.

The position of the collar 33 as shown in Fig. 3 is such that the balls 36 are in contact both with the rod 15 and the beveled surface 28 of the housing 21, in which position the balls lock the

rod 15 against movement inwardly of the housing but permit movement outwardly as desired to increase the length of the support. The retaining means is shown in Fig. 4 in released position, wherein the collar 33 has been moved towards the outer end of the housing an amount sufficient that the balls 36 no longer contact with the beveled surface 28. In this position of the collar 33 and the balls 36, the rod 15 can be moved in either direction. The movement of the collar 33 from locking to released position and vice versa is accomplished by a pair of pins 39 and 40 mounted on the rod 15 with their ends projecting into the oppositely positioned grooves 18. In Fig. 4, it will be observed that the rod 15 has been moved outwardly to a point where the spring band 41 is in contact with a shoulder in the housing 21 at the lower end of the peripheral surface 32. In this position of the rod 15, the pin 40 is brought into contact with the lugs 35 on the collar 33 and thus moves the collar outwardly an amount sufficient to release the balls 36 from contact with the housing. In order that the collar 33 be moved to operative locking position, it is then necessary to move the rod 15 inwardly until the upper pin 39 contacts with the lugs 35 and returns the band to its original position as shown in Fig. 3. The locking position of the retaining means is thereby obtained as described by moving the rod 15 inwardly the maximum allowable amount and the releasing position is obtained by moving the rod outwardly the maximum allowable amount with the retaining means in locking position. Obviously the length of the support can be extended in any desired amount up to the maximum by merely exerting a pull tending to separate the upper and lower portions of the support, the retaining means meanwhile remaining in locking position and preventing any downward movement. In the event it is desired to shorten the length of the support, this is accomplished by pulling the rod 15 out the maximum amount and then moving the rod inwardly the maximum allowable amount and then moving the rod outwardly to the desired point.

Fig. 2 illustrates a plurality of extensible supports as hereinbefore described providing a mounting for an unattached stool, the members 12 each being supported by a lug 44 as shown. Upper and lower cross braces 45 hold the supporting members in fixed relation. The upper cross member 45 is shown in Figs. 3 and 4 as clamped between the lower end of the housing 21 and a shoulder on the upper end of the member 12. Stools of this character are portable and are generally carried from place to place by grasping the seat 10. The frictional contact of the band 41 with the inner periphery of the member 12 permits the lifting of the stool in this manner without danger of the members 15 being pulled outwardly.

In either of the stool constructions shown in Figs. 1 and 2, the adjustment of the height can be obtained with the stool in vertical or in any other position merely by exerting the necessary force tending to pull the rod or rods 15 outwardly. The released position of the retaining means is accomplished in either construction by extending the rods 15 the maximum allowable amount. The locking position of the rods 15 is also obtained in either of the described constructions by pushing the rod or rods inwardly the maximum amount as hereinbefore described.

An alternative form of retaining means is shown in Fig. 8 wherein is provided a spring band

or collar 46 which is similar in all respects to the spring band or collar 33 except that the balls 36 are positioned in circular apertures 47 and a slightly modified form of housing 48 is used. The 5 apertures 47 have inwardly diverging bounding walls whereby gravity keeps the balls in the apertures in contact with the rod 15. This embodiment of the invention is manipulated in the same manner for extending the rod 15 and for releasing the retaining mechanism as hereinbefore described in connection with the spring band or collar 33.

Still another form of retaining means is shown in Figs. 9, 10 and 11 comprising a housing 59 of 15 slightly larger diameter than shown for the housings 21 and 48 already described. The housing 59 provides a chamber 51 in which is mounted a collar 54 having an annular flange 55. The chamber 51 is bounded by downwardly converging side walls terminating in a shoulder 52 and a cylindrical surface 61 of a diameter substantially greater than that of the locking rod 15. The cylindrical surface 61 terminates in a shoulder 53 providing a support for a spring band or 20 sleeve 59 of a construction similar to the collar 33. The sleeve 59 has a plurality of stems 69 projecting from its upper end contacting with the flange 55 and thereby providing a support for the collar 54. The sleeve 59 has a pair of oppositely positioned lugs 57 positioned in the grooves 13 of the rod 15. The groove 19 of the rod 15 is positioned adjacent one of the grooves 13 as best 25 shown in Fig. 10 and provides a runway for a key 68 projecting from the collar 54. The spacing between the stems 69 registers with the apertures 36 and provides room for contact of the balls 36 with the rod 15.

The device is shown in Fig. 9 with the balls 36 in contact with the housing 59, in which position the rod 15 is locked against downward movement. This form of the device is manipulated in the same manner as already described for the embodiments shown in Figs. 1 to 8, inclusive. The device is released from locking position by moving the rod 15 upwardly to its maximum extended position, thereby bringing the pin 49 into contact with the lugs 57 and raising the sleeve 59 and the collar 54 against the resistance of the spring 38. The frictional contact of the sleeve 59 with the housing 59 prevents the spring 38 from moving the collar 54 and sleeve 59 downwardly when the device is in released position. The lower edges of the apertures 36 are inclined inwardly and downwardly and the collar 54 projects beyond the center of the balls 36 sufficiently that gravity tends constantly to hold the balls in contact with the rod 15 when the device is in released position.

Thus it will be seen that I have provided an 80 extensible supporting device for stools, and the like, and automatic locking means therefor which enables the supporting device to be extended any amount up to a predetermined maximum, the device being automatically locked against inward movement at any intermediate position and released from locking position by extending the support its maximum amount, and is again returned to locking position only upon complete retraction of the support.

Having thus described the invention, it is obvious that various immaterial modifications may be 85 made in the same; hence I do not limit myself to the exact form, construction and arrangement of parts herein shown and described, or uses mentioned.

What I claim as new and desire to secure by Letters Patent is:

1. An extensible member of the kind described comprising inner and outer telescoping members, a casing mounted on one end of the outer member and having a chamber with side walls converging towards the inner member, a collar having one end projecting into the chamber and its other end in frictional contact with the casing adjacent the small end of the chamber, said inner member extending through said chamber and collar, the projecting end of said collar provided with a plurality of recesses, a plurality of ball bearings mounted one in each of said recesses, means maintaining said ball bearings in their respective recesses in constant contact with said inner member, means operable upon movement of said inner member to its extreme inward position to move said collar to a position wherein the ball bearings also contact with said side walls, and means operable to move said collar to a position wherein the ball bearings clear said side walls upon outward movement of said inner member to its extreme outward position. 10

2. In an adjustable stool having a seat, an extensible support for the seat comprising a lower member and an upper member telescoping within the lower, a casing on the upper end of the lower member having a chamber bounded by downwardly converging walls, a collar frictionally engaging the casing below and projecting into the chamber, said upper member extending through said chamber and collar, said collar having a plurality of recesses in said projecting end, a plurality of ball bearings each mounted in one of said recesses in contact with said upper member, means operable by inward movement of said upper member to move said collar to a position where said ball bearings contact with said converging walls, and means operable upon movement of said upper member outwardly a predetermined amount to move said collar to a position wherein the ball bearings are disconnected from said converging walls. 25

3. In an adjustable stool having a seat, an extensible support for the seat comprising a lower member and an upper member telescoping within the lower, a casing mounted on the upper end of the lower member having a frusto-conical chamber bounded by downwardly converging side walls, a collar frictionally engaging the casing below and projecting into the chamber, said upper member extending through said chamber and collar, said collar providing a plurality of recesses in its projecting end, a plurality of ball 30 bearings mounted one in each of said recesses in contact with said upper member, said upper member provided with means for moving the collar at substantially the end of the travel of the inner member in either direction, whereby said ball bearings are released from contact with said converging side walls when the upper member is drawn to its extreme outward position and remain in released position until the upper member has been retracted to the limit of its inward movement, and means operable to move said collar to a position wherein the ball bearings contact with said converging side walls upon retraction of said upper member to the limit of its inward movement. 35

4. In an adjustable stool having a seat, an extensible support for the seat comprising a lower member and an upper member telescoping within the lower, a casing mounted on the upper end of the lower member and having a chamber bounded 40

75

by downwardly converging side walls, a collar frictionally engaging the casing below and projecting into the chamber, the upper member extending through said chamber and collar, a plurality of ball bearings mounted in said chamber, said collar having a plurality of recesses in its projecting end each providing a mounting for one of said ball bearings, means maintaining said ball bearings in contact with said upper member, means operable by retraction of said upper member to its extreme inward position to move said collar to a position where said ball bearings contact with said converging side walls, and means operable upon movement of the upper member to its extreme outward position to move said collar to a position wherein the ball bearings are disengaged from said side walls.

locking relation between said wall and said support upon downward movement of said support, unlocking means relative to which said support is movable for lifting said free rolling member out of locking engagement with said support, and means on said support actuating said unlocking means as said support is lifted to its upper limit to permit lowering of said support.

disengaged from said side walls.

5. In an extensible construction, the combination of a supporting shaft movable axially for adjustment, a retainer fixed in position and embracing said shaft and having an inner surface angularly arranged with respect to said shaft, a free rolling member arranged between the angularly disposed face of the retainer and the presented face of the shaft and normally maintained in contact with said faces so that movement of the shaft in one direction moves said free rolling member into wedged locking position to restrain movement of the shaft in said direction while permitting movement in the other, and means located within the retainer for moving said free rolling member to inoperative position to permit movement of the shaft in the first mentioned direction, said shaft having a part for moving said means to release said free rolling member at the end of the shaft movement.

8. In an adjustable stool and the like, the combination of a tubular casing having a chamber whose interior walls converge downwardly, a support slidably mounted in said casing, a free rolling member in said chamber engaging its converging wall and the presented surface of said support and adapted to be moved into wedged locking relation between said wall and said support upon downward movement of said support, unlocking means separate from said support for lifting and supporting said free rolling member out of locking position to permit lowering of said support, and means operating as said support is moved to its uppermost position for actuating said unlocking means. 10 15 20

6. In an extensible construction, the combination of a supporting shaft movable axially for adjustment, a retainer fixed in position and embracing said shaft and having an inner surface angularly arranged with respect to said shaft, a free rolling member arranged between the angularly disposed face of the retainer and the presented face of the shaft and normally maintained in contact with said faces so that movement of the shaft in one direction moves said free rolling member into wedged locking position to restrain movement of the shaft in said direction while permitting movement in the other, a sleeve arranged between said retainer and said shaft and adapted to move in between the converging faces of said shaft and retainer to move said free rolling member out of locking engagement therewith, means operable by the shaft in its movement for moving said sleeve at the end of the shaft movement in each direction, and means holding said sleeve in assumed positions.

9. In an adjustable stool and the like, the combination of a tubular casing having a chamber whose interior walls converge downwardly, a support slidably mounted in said casing, a free rolling member in said chamber engaging its converging wall and the presented surface of said support and adapted to be moved into wedged locking relation between said wall and said support upon downward movement of said support, means mounted for sliding movement in said casing for lifting and sustaining said free rolling member during lowering movement of said support, and means on said support operable at the end of its upward movement for actuating said sliding means. 35

7. In an adjustable stool and the like, the combination of a tubular casing having a chamber whose interior walls converge downwardly, a support slidably mounted in said casing, a free rolling member in said chamber engaging its converging wall and the presented surface of said support and adapted to be moved into wedged

10. In an extensible construction, the combination of a supporting shaft movable axially for 40 adjustment, a retainer fixed in position and embracing said shaft and having an inner surface angularly arranged with respect to said shaft, a free rolling member arranged between the angularly disposed face of the retainer and the presented face of the shaft and normally maintained in contact with said faces so that movement of the shaft in one direction moves said free rolling member into wedged locking position to restrain movement of the shaft in said direction while 50 permitting movement in the other, a sleeve arranged between said retainer and said shaft, means operable by the shaft at the end of the movement of the shaft in one direction for moving said sleeve in between the converging faces 55 of said shaft and retainer to move said free rolling member out of locking engagement therewith, and means operable by the shaft at the end of the movement of the shaft in an opposite direction for moving said sleeve from between said converging faces and said shaft, to permit said free 60 rolling member to move into locking engagement with said shaft.

JAMES A. CAMPBELL.
